Steve Myers
INVENTOR

Victor J. Evans

ATTORNEY

WITNESS: J. J. L. Wright

UNITED STATES PATENT OFFICE.

STEVE MYERS, OF RUFFSDALE, PENNSYLVANIA.

RAIL JOINT.

Application filed November 22, 1926. Serial No. 150,073.

This invention relates to a rail joint, the general object of the invention being to provide a seat forming plate which is adapted to rest upon two ties and to receive the ends 5 of two rails on its seat, with means for locking the rail ends to the plate.

Another object of the invention is to provide anchors for engaging the rails and which pass through the plate, with pins 10 which form parts of the above mentioned locking means for holding the anchors in place.

A still further object of the invention is to provide a locking plate for holding the 15 locking pins in position, with spikes for spiking the locking plate to the ties, some of these spikes engaging the seat forming plate.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:

Figure 1 is a sectional view through a portion of a track and showing two rail ends in elevation, with my improvement in use.

Figure 2 is a section on line 2—2 of Figure 1.

Figure 3 is a plan view of Figure 1.

Figure 4 is a plan view of the seat forming plate.

Figure 5 is a plan view of the locking plate for the pins.

Figure 6 is an edge view of said plate.

Figure 7 is an end view thereof.

Figure 8 is an elevation of a portion of 45 a rail.

Figure 9 is a section on line 9—9 of Figure 3.

Figure 10 is a view of one of the anchors.

Figure 11 is a view of a tool used for 50 driving a locking pin out of the lugs.

In these views, 1 indicates a plate which is formed with a longitudinally extending recess 2 which forms a seat for the abutting

ends of the rails A, the plate being long enough to extend over two or more ties B. 55 Each rail, adjacent its ends, is provided with the depending lugs 3 which are perforated and the plate is provided with the elongated openings 4 through which the lugs at the abutting ends of the two rails pass. 60 The ends of these openings 4 extend beyond the seat so that L-shaped anchors 5 can have their long arms placed in the ends of the openings with the short arms engaging the base of the rails, as shown in Figures 1, 2, 65 3 and 9. The anchors are also provided with perforations in their lower ends which will register with the holes in the lugs 3 when the anchor parts are in place. Perforated lugs 6 also depend from the bottom 70 of the plate 1 and these lugs are arranged in pairs adjacent the opposite edges of the plates, with their perforations in line with the perforations of the lugs 3 of the rail. Thus after the rail ends are placed on the 75 plate and the anchors dropped in the ends of the openings 4, a pin 7 is passed through the perforations or holes in each set of the lugs 6 of the plate, a lug 3 of the rail and the anchors 5 so that the rail is locked to the plate by the pin engaging the lugs 3 and 6 and also by the anchors which are held in place by the pin and which engage the rail base.

Each pin is provided with a head 8 having its upper edge in the same plane as the body of the pin so that the pin can rest snugly against the under face of the plate. In order to hold the pins in place, I provide a locking plate 9 which is provided with the depending flanges 10 which engage the heads of the pins. The outer edge of the locking plate is beveled, as at 11, so that it will be held in place by the spikes 12, the heads of which engage the beveled portions and which are driven into the ties. The locking plate is also provided with the inwardly extending perforated ears 13 which are adapted to engage the notches 14 in the outer edge of the plate 1, the perforations receiving the spikes 15 which not only act to fasten the inner edge of the locking plate to the ties, but also act to lock the outer edge of the plate 1 to the ties. The inner edge of the plate is provided with 100 the notches 16 to receive the spikes 17 for

fastening the inner edge of the plate to the ties.

A tool, such as shown in Figure 11, may be used for knocking the pins 7 out of engagement with the parts, said tool consisting of a shank 18, a head 19 and a handle 20 which projects upwardly from the head. Thus by grasping the handle the shank can be placed against the end of a pin and then 10 by striking the head with a hammer or the like the pin can be driven out of the lugs and anchors, it first being necessary to remove the locking plate 9.

From the foregoing, it will be seen that 15 I have provided means for firmly fastening the abutting ends of a pair of rails together and to two or more ties so that there is no danger of the ends of the rails getting out of alignment or of the rails spreading.

20 The plate 1 is provided with reinforcement 21 on its under face which are so located as to come between the two ties, as shown in Figure 1.

It is thought from the foregoing description that the advantages and novel features 25 of my invention will be readily apparent.

I desire it to be understood that I may make changes in the construction and in the combination and arrangement of the several 30 parts, provided that such changes fall within the scope of the appended claims.

What I claim is:—

1. In combination with a pair of rails having depending perforated lugs adjacent 35 their abutting ends, a seat forming plate for the rails having pairs of depending perforated lugs, each pair of lugs on the plate being in register with a lug on a rail, the plate being provided with openings through which 40 the lugs on the rails extend and pins passing through the lugs for connecting the rail to the plate.

2. In combination with a pair of rails having depending perforated lugs adjacent 45 their abutting ends, a seat forming plate for the rails having pairs of depending perforated lugs, each pair of lugs on the plate being in register with a lug on a rail, the plate being provided with openings through which 50 the lugs on the rails extend, pins passing through the lugs for connecting the rail to the plate and locking means for holding the pins in place.

3. In combination with a pair of rails 55 having depending perforated lugs adjacent their abutting ends, a seat forming plate for the rails having pairs of depending perforated lugs, each pair of lugs on the plate being in register with a lug on a rail, the 60 plate being provided with openings through which the lugs on the rails extend, anchors passing through the ends of the openings in the plate and having their upper ends engaging the bases of the rails with their lower 65 ends perforated, the lower ends of the an-

chors being located between the lugs of the plate and a lug on a rail and pins passing through the lugs and anchors for holding the parts together.

4. In combination with a pair of rails having depending perforated lugs adjacent 70 their abutting ends, a seat forming plate for the rails having pairs of depending perforated lugs, each pair of lugs on the plate being in register with a lug on a rail, the 75 plate being provided with openings through which the lugs on the rails extend, anchors passing through the ends of the openings in the plate and having their upper ends engaging the bases of the rails with their 80 lower ends perforated, the lower ends of the anchors being located between the lugs of the plate and a lug on a rail, pins passing through the lugs and anchors for holding the parts together and a locking plate for 85 holding the pins in place.

5. In combination with a pair of rails having depending perforated lugs adjacent 90 their abutting ends, a seat forming plate for the rails having pairs of depending perforated lugs, each pair of lugs on the plate being in register with a lug on a rail, the 95 plate being provided with openings through which the lugs on the rails extend, anchors passing through the ends of the openings in the plate and having their upper ends engaging the bases of the rails with their lower 100 ends perforated, the lower ends of the anchors being located between the lugs of the plate and a lug on a rail, pins passing through the lugs and anchors for holding the parts together, a locking plate for holding the pins in place and spikes for holding the plate and locking plate to ties.

6. In combination with a pair of rails 105 having depending perforated lugs adjacent their abutting ends, a seat forming plate for the rails having pairs of depending perforated lugs, each pair of lugs on the plate being in register with a lug on a rail, the 110 plate being provided with openings through which the lugs on the rails extend, anchors passing through the ends of the openings in the plate and having their upper ends engaging the bases of the rails with their lower 115 ends perforated, the lower ends of the anchors being located between the lugs of the plate and a lug on a rail, pins passing through the lugs and anchors for holding the parts together, a locking plate for holding the pins in place, spikes for holding the plate and locking plate to ties, said locking plate having perforated inwardly extending ears and one edge of the seat forming plate having notches for receiving the ears, some 120 of the spikes passing through the perforations in the ears and engaging parts of the seat forming plate.

7. In combination with a pair of rails having depending perforated lugs adjacent 130

their abutting ends, a plate having a longitudinally extending recess forming a seat for the abutting ends of the rails, said plate also having openings therein for receiving the lugs on the rails, L-shaped anchors passing through the ends of the openings in the plate and having their heads engaging the rail bases, depending perforated lugs on the

plate, locking pins passing through the lugs on the plate, the anchors and the lugs on the rails for locking the parts together, a locking plate for holding the pins in position and spikes for fastening the locking plate and the seat forming plate to ties. **10**

In testimony whereof I affix my signature.
STEVE MYERS.
